UNITED STATES PATENT OFFICE

92,044

DESIGN FOR A POT HOLDER

Helen I. Snyder, Chicago, Ill., assignor to Albert
B. Collingbourne, Elgin, Ill.

Application February 19, 1934, Serial No. 50,769

Term of patent 7 years

To all whom it may concern:

Be it known that I, HELEN I. SNYDER, a citizen of the United States, residing at Chicago, in the county of Cook and State of Illinois, have invented a new, original, and ornamental Design for a Pot Holder, of which the following is a specification, reference being had to the accompanying drawing, forming part thereof.

In the drawing:—

Fig. 1 is a front view of a pot holder embodying my design.

Fig. 2 is a side elevation of the same.

I claim:—

The ornamental design for a pot holder as shown.

HELEN I. SNYDER.
